ASH REMOVING DEVICE

Larry M. Henning, Columbus, Ohio

Application April 3, 1937, Serial No. 134,861

3 Claims. (Cl. 126—244)

This invention relates to ash removing devices and has for an object to provide a tank, a tray, and a revoluble tray supporting frame in the ash pit of a furnace whereby the fine ashes 5 may be washed into a sluice-way or sewer to the end that the coarse ashes and coal may be removed from the ash pit without the usual objectionable cloud of fine ashes incident to the disposal of ashes from a furnace.

10 A further object of the invention is to provide a device of this character which will be formed of a few strong simple and durable parts, which will be easy to install and operate, which will be inexpensive to manufacture, and which will not 15 easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawings forming part of 25 this specification,

Figure 1 is a longitudinal sectional view of an ash pit of a furnace showing an ash removing device therein constructed in accordance with the invention.

30 Figure 2 is a horizontal sectional view taken on the line 2—2 of Figure 1 looking in the direction of the arrowheads.

Figure 3 is a vertical sectional view taken on the line 3—3 of Figure 2 looking in the direction 35 of the arrowheads.

Figure 4 is a detail perspective view of the rotatable ash tray supporting frame.

Figure 5 is a detail perspective view of the tank.

Referring now to the drawings in which like 40 characters of reference designate similar parts in the various views, 10 designates a fire box, 11 the grate, 12 the ash pit, and 13 the ash pit door, of a conventional furnace.

In carrying out the invention a circular tank 45 14, best shown in Figure 5, is provided with a circumferential flange 15 on the bottom for supporting the tank upon the bottom of the ash pit. The tank is provided with a central bearing recess 9 on the top face of the bottom. The tank 50 is further provided with a valve controlled water supply pipe 16, best shown in Figure 2, and with a valve controlled outlet pipe 17 which may be connected to any convenient sluice-way or sewer.

The tray supporting frame 18, best shown in 55 Figure 4, comprises a bottom formed of longi-

tudinal bars 19 connected centrally by a cross bar 20, these bars all lying in the same plane. The bottom is substantially the same in length as the diameter of the tank 14 and is provided with arcuate upstanding end bars 21 which, as best shown in Figure 2, are spaced from the wall of the tank 14. Skeleton side walls 22 rise from the outer bars 19 of the bottom and support a cross bar 23 to which is fixed an upright shaft 24 for rotating the frame.

The frame is provided on the cross bar 20 of the bottom with a depending gudgeon 25, best shown in Figures 1 and 3 and this gudgeon fits in the central bearing recess 9 of the tank to rotatably mount the frame in the tank. For rotating the frame a shaft 26 projects through an opening 27 in the ash pit, best shown in Figure 3, and the outer end of the shaft is equipped with a crank handle 28. The inner end of the shaft is geared to the stand shaft 24 of the frame by bevel gears 29 and 30.

Inclined brace bars 31, best shown in Figures 2 and 3, are connected at the inner ends to a stationary sleeve 32, which rotatably receives the upper end of the stand shaft 24, and are bolted 25 at the outer ends to the ash pit, as shown at 33.

30 A tray 34 is removably mounted in the frame 18 and the tray comprises longitudinal side walls 35, arcuate end walls 36, the latter being equipped with handles 37, and a reticulate bottom 38. The tray is of sufficient height to slide easily over the end bars 21 of the frame during removal and insertion of the tray.

35 A funnel 39, best shown in Figure 1, is secured to the top of the ash pit in any preferred manner and is substantially the same shape as the tray so that when the ashes are dumped the ashes will be deposited in the tray.

In operation the tank 14 is filled with water. The ashes are now dumped in the conventional 40 manner, care being taken that the tray is disposed in registration with the funnel. The crank handle 28 is now rotated so that all of the fine ashes and dust will be washed into the tank leaving only clean ashes and coal in the tray. The 45 tray may now be removed from the tray supporting frame 18 and withdrawn through the open ash pit door 13 for depositing the ashes in any convenient location without the usual cloud of dust. Before the empty tray is inserted in the 50 tray supporting frame the muddy water in the tank 14 is withdrawn by opening the valve in the outlet pipe 17 so that the fine ashes and dust and water may be carried off into the sluice-way or sewer.

From the above description it is thought that the construction and operation of the invention will be fully understood without further explanation.

5. What is claimed is:

1. In a furnace having an ash pit, a water tank in the ash pit, means for supplying and withdrawing water from the tank, a tray supporting frame rotatably mounted in the tank, a tray in the frame, and means connected to the frame and accessible exteriorly of the ash pit for rotating the tray and frame in the tank to wash dirt and fine ashes from the tray into the tank after each dumping of the furnace.
- 10 2. In a furnace having an ash pit, a funnel in the top of the ash pit, a water tank below the funnel, means for supplying and removing water from the tank, a frame rotatably mounted in the tank below the funnel, a tray removably supported in the frame in registration with the funnel and adapted to receive ashes therefrom when the furnace is dumped, a stub shaft rising from the frame, a shaft geared to the stub shaft and extending exteriorly of the ash pit, and means on 15 the last named shaft for rotating the shaft to

rotate the tray and frame in the tank for washing dirt and fine ashes into the tank after the furnace is dumped.

3. In a furnace having an ash pit, a tank in the bottom of the ash pit, valve controlled pipes 5 entering the ash pit and the tank for supplying the tank with water and draining water from the tank, said tank being substantially circular in contour and having a central bearing recess in the top face of the bottom, a tray supporting 10 frame having a depending gudgeon fitting in said bearing recess and rotatably mounting the frame in the tank, a stand shaft on the frame, a shaft geared to the stand shaft and projecting exteriorly of the ash pit, means on the last named 15 shaft for rotating the shaft, a funnel secured to the top of the ash pit, a tray in the frame having a reticulate bottom, the tray and the funnel being of substantially the same shape so that when the ashes are dumped the ashes will be deposited in the tray, and means at the ends of the frame permitting of the tray being withdrawn 20 endwise through the frame and the ash pit door.
